US00D684916S

(12) **United States Design Patent**
Ashida et al.

(10) **Patent No.:** US D684,916 S
(45) **Date of Patent:** ** Jun. 25, 2013

(54) **ELECTRONIC COMPUTER**

(75) Inventors: **Kenichiro Ashida**, Kyoto (JP); **Masato Ibuki**, Kyoto (JP); **Shinji Yamamoto**, Kyoto (JP); **Fumiyoishi Suetake**, Kyoto (JP); **Akiko Suga**, Kyoto (JP); **Naoya Yamamoto**, Kyoto (JP); **Hitoshi Tsuchiya**, Kyoto (JP); **Junji Takamoto**, Kyoto (JP); **Noboru Wakitani**, Kyoto (JP); **Yasuhisa Kitano**, Kyoto (JP); **Toshiaki Iwao**, Kyoto (JP); **Yuji Hori**, Kyoto (JP); **Takafumi Nishida**, Kyoto (JP); **Hiroti Ikuta**, Kyoto (JP)

(73) Assignee: **Nintendo Co., Ltd.**, Kyoto (JP)

(**) Term: **14 Years**

(21) Appl. No.: **29/407,696**

(22) Filed: **Dec. 1, 2011**

(30) **Foreign Application Priority Data**

Jun. 3, 2011 (JP) 2011-012712
Jun. 3, 2011 (JP) 2011-012713

(57) **CLAIM**

The ornamental design for an electronic computer, as shown and described.

DESCRIPTION

FIG. 1 is front, left and top perspective view of an electronic computer showing our new design;

FIG. 2 is rear, right and bottom perspective view thereof;

FIG. 3 is a top plan view thereof;

FIG. 4 is a bottom plan view thereof;

FIG. 5 is a front view thereof;

FIG. 6 is a rear view thereof;

FIG. 7 is a left side view thereof; and,

FIG. 8 is a right side view thereof.
